UNITED STATES PATENT OFFICE

AUGUST L. SEGELHORST, OF HUNTINGTON BEACH, CALIFORNIA

AUTOMATIC SLIP HANDLER

Application filed March 28, 1930. Serial No. 439,022.

This invention has to do with slips such as are commonly used to support a string of pipe, and is more particularly related to the art of drilling and operating oil wells where-
3 in the drill pipe, the casing and the tubing are usually supported and handled by means of slips associated with suitable supporting and handling spiders.

It is a primary object of this invention to
10 produce a slip assembly of the class described, which is of simple form and construction, may be economically manufactured and can be easily installed and handled in the field.

It is well known to those familiar with the
15 art that the operation of the slips in oil well drilling tools requires a certain amount of skill on the part of the workmen and since some of these slips are necessarily very large and consequently very heavy, they are in
20 many cases difficult to operate.

It therefore becomes a further object of this invention to produce a slip handling device of the class described, which is automatic in its action, and to accomplish this
25 object I have produced a slip handler in which the movement of the slips is controlled by the movement of a string of pipe or tubing therethrough, thereby eliminating the manual labor ordinarily required to operate the
30 slips. This operation is effected by providing the slips with a yieldable member which extends inwardly into the opening through which the tubing passes, so as to be in continual pressure engagement with the tubing
35 and the friction of the tubing upon this yieldable member is, therefore, effective to exert a force upon the slips in the direction in which the tubing is moving. The yieldable member referred to may be mounted directly upon the slips, it may be mounted in a specially constructed slip control ring which is attached to the slip through the medium of yieldable members adapted to permit the inward and outward movement of the slips relative to the tubing, or it may be an independent ring contained within the housing and adapted to move the slips by virtue of its engagement therewith.

It will be understood, of course, that the inward and outward movement of the slips

relative to the tubing is effected in the usual manner by slidably mounting the slips within a housing and forming the interengaging surfaces between the slips and the housing so as to obtain a wedge action upon the slips 55 and effect their inward movement toward the passage therethrough when they are pressed downwardly into the housing.

The slip handling device contemplated by this invention is especially useful in connection with slip assemblies wherein the interengaging surfaces between the housing and the slips are formed so as to provide interfitting shoulders which limit the upward movement of the slips in the housing. It is 60 to be understood, however, that the invention is not confined in its use to an assembly of this nature, but readily lends itself to use in connection with numerous types of slips and slip assemblies, examples of which will be 65 hereinafter more completely described.

In order that the slips may optionally be held against downward movement in the housing during the process of lowering the tubing therethrough, it becomes a further 75 object of this invention to provide a device of the class described with a latch unit which is adapted to lock the slips in their upper position.

In some cases, especially in the event the 80 slips are being used in a casinghead, it becomes desirable to have embodied in the slip assembly a packing unit which is formed so as to provide a tight closure between the tubing and the casing or the slip housing. 85 It is, therefore, another object of this invention to produce a device of the class described, wherein the yieldable member referred to above is so formed and so positioned either upon the slips or upon the slip control collar, 90 as to be forced into pressure engagement with the inner surface of the housing when it is engaged by the tubing.

The details in the construction of various forms of my invention, together with other 95 objects attending its production, will be best understood from the following description of the accompanying drawings which are chosen for illustrative purposes only, and in which Fig. 1 is a sectional elevation of a preferred 100

form of slip assembly contemplated by this invention, which is shown as being mounted in the upper end of an oil well casing and shows the lower end portion of a string of pipe or tubing as having been lowered into the upper end portion of the slip assembly;

Fig. 2 is a sectional elevation similar to Fig. 1 and illustrating the manner in which the slips are operated by the movement of a tubing therethrough;

Fig. 3 is a plan section which may be considered as having been taken in a plane represented by the line 3—3 in Fig. 1;

Fig. 4 is a plan section taken through a unit embodying my invention and shows the manner in which the slips and the slip handler may be placed about a tubing after the same has been started into the casing;

Fig. 5 is a partial sectional elevation illustrating the details of the construction of a modified form of my invention;

Fig. 6 is another partial sectional elevation showing another modification in the construction of the yieldable slip control member;

Fig. 7 is a partial sectional elevation showing another modified form of my invention in which the yieldable slip control member is mounted directly upon the slips;

Fig. 8 is a plan section taken in a plane represented by the line 8—8 in Fig. 7;

Fig. 9 is a partial sectional elevation showing another modified form of my invention in which the slip control ring is positioned above the slips;

Fig. 10 is a partial sectional elevation illustrating the adaptation of the automatic slip handler to the simplest form of slip commonly used in the oil well industry.

Fig. 11 is a sectional elevation showing the manner in which my invention may be adapted to a lifting nipple.

More particularly describing the invention as herein illustrated, reference numeral 11 indicates a slip supporting unit which is shown as comprising the top collar on a string of casing, but it will be understood that this member may be a part of an elevator, the spider in a rotary table, or any other member which is used for supporting or handling pipe. Reference numeral 12 indicates a slip housing which is shown as being in threaded engagement with the supporting member 11, and is provided with an inwardly and downwardly sloping inner surface 13 against which a plurality of slips 14 are adapted to rest in sliding engagement. The upper portion of the collar 12 is provided with a recess forming an inwardly extending shoulder 15, which is adapted to cooperate with outwardly extending shoulders 16, formed on the slips 14 for the purpose of limiting the upward movement of the slips through the housing.

Reference numeral 17 indicates what may

be termed a guide member, which is shown as being in the form of an internally threaded collar having a top plate 18 provided with an opening 19 through which a tubing 20 is adapted to pass. The guide member 17 is provided for the purpose of directing the tubing 20 into the passage surrounded by the slips and to thereby prevent the inadvertent movement of one of the slips into the passage through engagement of the tubing therewith.

Reference numeral 21 indicates what I will hereinafter refer to as a slip control ring or collar which may be made solid but is shown as being made up of a plurality of segments 22 which are retained in assembled relation with each other by means of a clamping ring 24 which is positioned in an annular groove 25 in the assembly collar. The slip control collar or ring 21 is attached to the slips 14 by a plurality of metal bands or strips 26, and it will be observed that each of the individual slips 14 is provided with a separate collar segment 22. Mounted upon the lower end portion of the collar 21 is a yieldable tubing engaging member 27. This member is preferably made as a solid ring which is fitted into aligned grooves 28 formed in the lower ends of the sections 22, or is otherwise attached to the collar. In this particular form of my invention the member 27 is formed so as to be pressed outwardly into pressure engagement with the inner surface of the housing 12 when its inner edge is engaged by the tubing 20. This feature of the invention is clearly illustrated in Fig. 2, where it will be understood that the yieldable member 27 acts as a packer between the tubing 20 and the housing 12. It will be understood in this connection that the yieldable member 27 may be composed of any suitable material, but for the most satisfactory results I have found that this member should be made of rubber.

It was previously mentioned as one of the objects of this invention to provide a device of the class described, with a latch unit which could be employed for locking the slips in their upper position so that the tubing might be lowered therethrough to any desired point before its movement was halted through its engagement with the slips. Such a locking device is generally indicated in Figs. 1 to 3 inclusive, by reference numeral 30, and is shown as comprising a pin member 31 which extends through a suitable aperture 32 formed in the housing 12 and has an inner tapered end which is adapted to be received in an annular groove or a suitably positioned notch formed in the ring member 21 and indicated in the drawings by reference numeral 33. The pin member 31 is shown as extending outwardly through a suitably positioned housing 34 which contains a coil spring 35 adapted to engage a shoulder 36 formed on the pin 31, and through such engagement to continually press the spring inwardly to-

ward the position shown in Fig. 1, where it is received by the recess 33 and is effective to hold or lock the slips in their upper position. The outward or releasing movement 5 of the pin 31 is effected by means of a lever 37 which is pivotally mounted on the outwardly extending end of the pin and is provided with an elongated cam surface 38, which when engaged by the outer surface of 10 the housing 34, as indicated in Fig. 2, is effective to withdraw the pin from the recess 33 and thereby permit the downward movement of the slips in the housing 12.

In the operation of this device it will be understood that the units shown in Figs. 1 to 15 3 inclusive, may be assembled and installed upon this pipe supporting or handling member and that the tubing may be lowered there-through to the desired point, after which the 20 latch can be released and the tubing locked in any predetermined position.

In some instances it is desirable to install the slip assembly upon the tubing after it has started into a well, or at a point appreciably 25 above its lower end. Under such circumstances I have found it desirable to employ a special clamping tool which I have devised for use in connection with this device, and such a tool is shown in Fig. 4 as comprising 30 a yoke 40 having an engagement plate 41 mounted upon one end and provided with a threaded hub 42 at its other end. The threaded hub 42 receives a screw member 43 which carries on its inner end an engagement 35 member 44 and on its outer end a crank 45. In assembling the unit upon a tubing by means of this device, the slip control ring 21 is positioned about the tubing and is clamped in assembled relation thereon by 40 means of the engagement members 41 and 44 in cooperation with the screw 43. After all of the segments 22 have been clamped into tight engagement with each other, the ring 24 is placed in the annular channel 25 45 and after being fastened in any preferred manner, such as by means of the screws 46, the clamping member 40 is removed and the slip assembly is ready for operation.

That form of my invention shown in Fig. 50 5 is substantially the same as the form described in connection with Figs. 1 to 4 inclusive, and for this reason parts similar to those described in connection with the above figure are indicated by the same reference 55 characters, distinguished by the letter "a". The main distinction between this modified form of my invention and the form described above, resides in the formation of the slip control ring 21a and the yieldable tubing 50 engaging member 27a. It will be noted that the slip control ring 21a is similar to the ring 21 except that it has formed upon its inner surface a channel 50 and that the tubing 55 engaging members 27a comprises a T shaped ring, the T section 51 of which is re-

ceived by the channel 50. In this form of my invention the pipe engaging member 27a does not act as a packer between the tubing 20a and the housing 12a, but is designed to act solely for the purpose of effecting a limited movement of the slips in the housing when the latch member 30a is released. 70

That form of my invention shown in Fig. 6 is fundamentally similar to the forms shown in Figs. 1 to 5 inclusive, and the parts similar 75 to those described in connection with the above figures are indicated by the reference characters used in Fig. 1, distinguished by the letter "b". In this form of my invention, instead of using a single slip control ring as 80 was employed in the forms described above, I use a pair of spaced parallel rings 52 and 53, which are connected by means of inwardly bowed spring members 54. The spring members 54 are shaped so that they 85 are in continual pressure engagement with the tubing 20b and through such engagement they have the same effect as the rubber members shown and described in connection with Figures 1 to 5, inclusive. In this form of my 90 invention, the latch member 30b, instead of engaging an annular groove, as was the case in the forms described above, is positioned so as to extend inwardly below the lower edge 95 of one of the rings (the ring 52).

In the form of my invention shown in Fig. 7, wherein the parts similar to those described in connection with the above figures are indicated by the reference numerals used in Fig. 1, distinguished by the letter "c", I show the 100 yieldable slip control member 27c as comprising a plurality of segments which are mounted directly upon the slips. In this form of my invention the slips themselves, indicated by reference numerals 14c, are 105 shown as being provided with an annular channel or a suitably positioned recess 56, which is situated so as to receive the latch pin 31c in the latch 30c. It will be understood in regard to this form of my invention, 110 that the yieldable slip control member 27c may be mounted in the manner shown in Fig. 7, or if desired, may be mounted on the bottom edge of the slip 14c so as to form a 115 packer in the same manner as was described in that form of my invention shown in Fig. 1. In order that the slips in this last mentioned form of my invention may be maintained in assembled relation with each other, it is necessary, since these slips are not associated with a slip control ring, to provide 120 some kind of a flexible connection between the adjacent slips. Such a connection is clearly illustrated in Fig. 8, as comprising a 125 plurality of slotted fingers 57, which are mounted in aligned grooves 58 formed in the top portions of the slips, these fingers being pivotally connected to one of the slips, as indicated by reference numeral 59, and being 130 provided with slots 60 in their opposite

end portions, which are slidable about pins 61.

In the operation of this last described form of my invention it will be understood that 6 when the latch member 30c is released, the engagement of the tubing 20c with the yieldable member 27c is effective to draw the slips downwardly into the dot and dash line position shown in Fig. 8, and to thereby lock 10 the tubing 20c against further downward movement with respect to the housing 12c.

In the form of my invention shown in Fig. 9, the housing 12d is shown as being provided with a uniformly tapered inner surface 15 face 65, against which the slips 14d rest in sliding engagement. It will be noted that the slips 14d are provided with uniformly sloping outer surfaces and that their upward movement with respect to the housing 12d is 20 limited by an inwardly projecting shoulder 66, which is formed upon a collar 67. In this form of my invention the slip control ring 21d is contained within the collar member 67 and is attached to the upper end portion of 25 the slips 14d through the medium of yieldable attaching members 26d. The slip control ring or collar 21d carries a yieldable engagement member 27d and is locked against downward movement with respect to the 30 housing 12d by means of a latch 30d which is positioned so that the latch pin 31d will extend inwardly through the collar member 67 below the bottom edge of the ring member 21d when the slips have been elevated to the 35 extreme upper position. The upward movement of the slip assembly with respect to the housing while the tubing is being withdrawn, is limited by means of an inwardly extending flange or shoulder 68, which is formed on the 40 upper end of the collar member 67.

The form of my invention shown in Fig. 10 embodies the simplest type of slip assembly which is commonly used in the oil well drilling industry, and shows the same as comprising 45 a slip housing 12e, which is adapted to receive slips 14e, the slips 14e being shown as having attached to their lower end portion through the medium of yieldable strips 26e, a slip control ring 21e. The slip control ring 50 21e is substantially the same as the one described in connection with Fig. 5. It will be understood, of course, that it may be made in the form of the one described in connection with Fig. 1, and the parts similar to those described in connection with Fig. 5 are indicated by the same reference characters, designated by the letter "e".

It is frequently desirable, especially in the 60 event one company is operating several wells which are near each other, to have what is known as a lifting nipple that may be taken from one well to another and used in withdrawing or installing tubing in the well. 65 Such a nipple consists of a short section of

tubing similar to that which is to be installed, having mounted thereon a set of slips. I have found that the device contemplated by this invention is particularly adapted to use in connection with such a nipple and in Fig. 11 I show a preferred form of assembly consisting of a nipple or short tubing section indicated by reference numeral 70, upon which a slip assembly 71 is mounted. The slip assembly 71 may be constructed as any one of the forms described above, but I show the same as comprising a unit in which the slip control collar is similar to the one shown and described in connection with Fig. 1, and the slip elements 14e' are similar to those shown in Fig. 10. The slip control collar and its associated parts indicated by the same reference characters as were used in connection with Fig. 1, are distinguished by the prime mark.

It will be apparent from the above description that the device contemplated by this invention comprises an automatic slip handler which is of simple form and construction and which lends itself to various forms and uses. It is to be understood that while I have herein described and illustrated various forms of my invention, the invention is not limited to any one of the structures described above, but includes within its scope whatever changes fairly come within the spirit of the appended claims.

I claim as my invention:

1. A slip organization for use in supporting tubing embodying the combination of: a housing; slips slidably mounted in said housing, said slips and said housing being provided upon their engaging faces with transverse recesses producing inter-fitting parts whereby the slips are adapted to move outwardly to clear the tubing when elevated and to be locked against upward movement within the housing in the elevated position; and yieldable means associated with said slips and in continual pressure engagement with said tubing for moving said slips in said housing into an engaging or a non-engaging relation with said tubing during a downward or upward movement of said tubing through said slips.

2. A slip organization for use in supporting tubing embodying the combination of: a housing; slips slidably mounted in said housing, said slips and said housing being provided upon their engaging faces with transverse recesses producing inter-fitting parts whereby the slips are adapted to move outwardly to clear the tubing when elevated and to be locked against upward movement within the housing in the elevated position; latch means for locking said slips in said elevated position; and yieldable means associated with said slips and adapted to engage said tubing for moving said slips in said housing during the movement of said tubing

therethrough when said latch means is released.

3. A slip organization for use in supporting tubing embodying the combination of:
5 a housing; slips slidably mounted in said housing, said slips and said housing being provided upon their engaging faces with transverse recesses producing inter-fitting parts whereby the slips are adapted to move
10 outwardly to clear the tubing when elevated and to be locked against upward movement within the housing in the elevated position; a slip control ring adapted to encircle said tubing; means connecting said slips to said ring; and yieldable means mounted on said ring and adapted to engage said tubing for moving said ring and said slips in said housing during the movement of a tubing there-through.

20 4. A slip organization for use in supporting tubing embodying the combination of: a housing; slips slidably mounted in said housing, said slips and said housing being provided upon their engaging faces with 25 transverse recesses producing inter-fitting parts whereby the slips are adapted to move outwardly to clear the tubing when elevated and to be locked against upward movement within the housing in the elevated position; 30 a slip control ring adapted to encircle said tubing; means connecting said slips to said ring; yieldable means mounted on said ring and adapted to engage said tubing for moving said ring and said slips in said housing 35 during the movement of a tubing therethrough; and a latch for locking said slips in an elevated position.

40 5. A slip organization for use in supporting tubing embodying the combination of:
a housing; slips slidably mounted in said housing, said slips and said housing being provided upon their engaging faces with transverse recesses producing inter-fitting parts whereby the slips are adapted to move outwardly to clear the tubing when elevated and to be locked against upward movement within the housing in the elevated position;
45 a slip control ring adapted to encircle said tubing; means connecting said slips to said ring; yieldable means mounted on said ring and adapted to engage said tubing for moving said ring and said slips in said housing during the movement of a tubing therethrough; and a latch in said housing cooperative with said ring for locking said slips in an elevated position.

6. A slip organization for use in supporting tubing embodying the combination of:
a housing; slips slidably mounted in said
housing, said slips and said housing being
provided upon their engaging faces with
transverse recesses producing inter-fitting
parts whereby the slips are adapted to move
outwardly to clear the tubing when elevated
and to be locked against upward movement

within the housing in the elevated position; a slip control ring adapted to encircle said tubing; means connecting said slips to said ring; yieldable means mounted on said ring and adapted to engage said tubing for moving said ring and said slips in said housing during the movement of a tubing therethrough, said ring being provided with an annular channel; and a latch in said housing adapted to engage the channel in said ring for holding said slips in an elevated position. 70 75

7. A slip organization for use in supporting tubing embodying the combination of: a housing; slips slidably mounted in said housing, said slips and said housing being provided upon their engaging faces with transverse recesses producing inter-fitting parts whereby the slips are adapted to move outwardly to clear the tubing when elevated and to be locked against upward movement within the housing in the elevated position; a slip control ring adapted to encircle said tubing; means connecting said slips to said ring; means mounted on said ring and adapted to engage said tubing for moving said ring and said slips in said housing during the movement of a tubing therethrough, said ring being formed in segments; and means for locking said segments in assembled relation about said tubing.

95
8. A slip organization for use in supporting tubing embodying the combination of: a housing; slips slidably mounted in said housing, said slips and said housing being provided upon their engaging faces with transverse recesses producing inter-fitting parts whereby the slips are adapted to move outwardly to clear the tubing when elevated and to be locked against upward movement within the housing in the elevated position; a slip control ring adapted to encircle said tubing; means connecting said slips to said ring; and a flexible yieldable ring mounted in said slip control ring and adapted to engage said tubing for moving said slip control ring and said slips in said housing during the movement of a tubing therethrough.
100
105
110

9. A slip organization for use in supporting tubing embodying the combination of: a housing; slips slidably mounted in said housing, said slips and said housing being provided upon their engaging faces with transverse recesses producing inter-fitting parts whereby the slips are adapted to move outwardly to clear the tubing when elevated and to be locked against upward movement within the housing in the elevated position; a slip control ring adapted to encircle said tubing; means connecting said slips to said ring; and a flexible yieldable ring mounted in said slip control ring adapted to engage said tubing for moving said slip control ring and said slips in said housing during the movement of a tubing therethrough, said flexible yieldable ring being mounted on the 115 120 125 130

bottom of said slip control ring and being shaped so as to form a packer between said tubing and said housing.

10. A slip organization for use in supporting tubing embodying the combination of: a housing; slips slidably mounted in said housing, said slips and said housing being provided upon their engaging faces with transverse recesses producing inter-fitting parts whereby the slips are adapted to move outwardly to clear the tubing when elevated and to be locked against upward movement within the housing in the elevated position; a slip control ring adapted to encircle said tubing; means connecting said slips to said ring; and a flexible yieldable ring mounted in said slip control ring adapted to engage said tubing for moving said slip control ring and said slips in said housing during the movement of a tubing therethrough, said flexible yieldable ring being formed so as to act as a packer between said tubing and said housing.

11. A slip organization for use in supporting tubing embodying: a housing; slips slidably mounted in said housing; and yieldable means associated with said slips and in continual pressure engagement with said tubing for imparting a limited movement to said slips during the passage of a tubing therethrough.

12. A slip organization for use in supporting tubing embodying: a housing; slips slidably mounted in said housing, said slips and said housing being provided with inter-engaging surfaces adapted to force said slips inwardly during their downward movement in said housing; and yieldable means associated with said slips in continual pressure engagement with said tubing for imparting limited movement to said slips in said housing during the passage of a tubing therethrough.

13. A slip organization for use in supporting tubing embodying: a housing; slips slidably mounted in said housing; yieldable means associated with said slips for imparting a limited movement to said slips during the passage of a tubing therethrough, and latch means in said housing for locking said slips against movement therein.

14. A slip organization for use in supporting tubing embodying: a housing; slips slidably mounted in said housing; and yieldable means associated with said slips for imparting a limited movement to said slips during the passage of a tubing therethrough, said yieldable means being formed so as to act as a packer between said tubing and said housing.

15. A slip organization for use in supporting tubing embodying: a housing; slips slidably mounted in said housing; a slip control ring adapted to encircle said tubing; means connecting said slips to said slip control ring; and a yieldable member mounted on said slip

control ring and adapted to engage said tubing for imparting limited movement to said slips in said housing during the passage of said tubing therethrough.

16. A slip organization for use in supporting tubing embodying: a housing; slips slidably mounted in said housing; a slip control ring adapted to encircle said tubing; means connecting said slips to said slip control ring; and a flexible yieldable ring mounted on said slip control ring and adapted to engage said tubing for imparting limited movement to said slips during the passage of a tubing therethrough.

17. A slip organization for use in supporting tubing embodying: a housing; slips slidably mounted in said housing; a slip control ring adapted to encircle said tubing; means connecting said slips to said slip control ring; and a flexible yieldable ring mounted on said slip control ring and adapted to engage said tubing for imparting limited movement to said slips during the passage of a tubing therethrough, said flexible yieldable ring being formed so as to act as a packer between said tubing and said housing.

18. A slip organization for use in supporting tubing embodying: a housing; slips slidably mounted in said housing; a slip control ring adapted to encircle said tubing; means connecting said slips in said slip control ring; a flexible yieldable ring mounted on said slip control ring and adapted to engage said tubing for imparting limited movement to said slips during the passage of a tubing therethrough, and a latch member in said housing for releasably holding said slips against movement in said housing.

19. A slip organization for use in supporting tubing embodying: a housing; slips slidably mounted in said housing; a slip control ring adapted to encircle said tubing; means connecting said slips in said slip control ring; a flexible yieldable ring mounted on said slip control ring and adapted to engage said tubing for imparting limited movement to said slips during the passage of a tubing therethrough, said flexible yieldable ring being formed so as to act as a packer between said tubing and said housing, and a latch member in said housing adapted to cooperate with said slip control ring for releasably holding said slips against movement in said housing.

20. A lifting nipple embodying the combination of: a short section of tubing; and a slip assembly on said tubing comprising a plurality of slips, means for holding said slips in assembled relation and yieldable means carried by said slips and in continual pressure engagement with said tubing for moving said slips with said tubing.

21. A lifting nipple embodying the combination of: a short section of tubing; and a slip assembly on said tubing comprising a

plurality of slips, means for holding said slips in assembled relation and means comprising a slip control collar attached to said slips and a yieldable member in said collar engaging 5 said tubing for moving said slips with said collar.

22. A slip organization for use in supporting tubing embodying: a housing; slips slidably mounted in said housing; yieldable 10 means mounted in said slips in continual pressure engagement with said tubing and movable by such pressure engagement to move the slips on movement of the tubing.

In testimony whereof, I have hereunto set 15 my hand at Los Angeles, California, this 18th day of March, 1930.

AUGUST L. SEGELHORST.
